EXTRUDED STRUCTURAL ELEMENT FOR BUILDINGS

Lindell N. Edwards, St. Louis, Mo., assignor to
Universal Modular Structures, Inc., St. Louis, Mo.

Filed Feb. 14, 1972, Ser. No. 226,370

Term of patent 14 years

Int. Cl. D25—01

U.S. Cl. D13—1 H

FIG. 1 is a perspective view of the upper end of an extruded structural element for buildings which embodies my new and ornamental design, and the hidden wide side of that extruded structural element is the mirror image of the exposed wide side, and

FIG. 2 is a sectional view, on an enlarged scale, through the extruded structural element for buildings shown in FIG. 1, and it is taken along the plane indicated by the line 2—2 in FIG. 1.

The extruded structural element for buildings is broken away at the lower end thereof in FIGS. 1 and 2 to indicate indeterminate length.

I claim:
The ornamental design for an extruded structural element for buildings, as shown and described.
